CLAIM

The ornamental design for a roller skate base plate, as shown and described.

DESCRIPTION

FIG. 1 is a perspective view of a roller skate base plate showing my new design;

FIG. 2 is a front view thereof;

FIG. 3 is a rear view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a right side elevational view thereof, the broken line showing of the skate shoe and wheels is for illustration only and forms no part of the claimed design.

FIG. 1

F I G. 2

F I G. 3

FIG. 4

FIG. 5

FIG. 6

FIG. 7
